CASH REGISTER

Ernst Breitling, Berlin, Germany, assignor to
The National Cash Register Company, Dayton, Ohio, a corporation of Maryland

Application July 6, 1935, Serial No. 30,126
In Germany July 12, 1934

10 Claims. (Cl. 235—8)

This invention relates to cash registers and the like but is more particularly directed to repeat mechanisms for such machines.

It is broadly an object of this invention to devise a unique repeat mechanism for cash registers and like machines.

A more specific object is to contrive means whereby the amount of the immediately preceding operation may be repeated without setting up a condition to effect said repeating during said preceding operation.

Another object is to provide means under control of a manipulative device to lock the amount differential members in the positions to which they were adjusted in the preceding operation in order to repeat the amount of said preceding operation.

Still another object is to provide an interlocking mechanism between the repeat starting bar and the amount keys to prevent the depression of both in the same operation.

A further object is to contrive means to prevent depression of the repeat starting bar when the total control lever is out of adding position, said means also adapted to lock the total control lever in adding position upon depression of the repeat bar.

With these and incidental objects in view, the invention includes certain novel features of construction and combination of parts, the essential elements of which are set forth in the appended claims and a preferred form or embodiment of which is hereinafter described with reference to the drawings which accompany and form a part of this specification.

In the drawings:

Fig. 1 is a cross-sectional view taken just to the right of one of the amount banks and depicts said amount bank and its associated differential mechanism.

Fig. 1A is a detail view showing the connections between the totalizer element and the main differential member.

Fig. 2 is a sectional view as observed from the right of the machine, illustrating the repeat starting bar and associated mechanism that locks the amount differentials during repeat operations.

Fig. 3 is a detail view of the total control lever and locking mechanism associated therewith.

Fig. 4 is a longitudinal sectional view as observed from the rear of the machine, taken along line 4—4 Fig. 1.

Fig. 5 is a detail view of the combined total

and repeat control lever for a modified form of repeat mechanism.

Fig. 6 is a sectional view as observed from the rear of the machine taken along line 6—6 Fig. 5.

5

GENERAL DESCRIPTION

The differential mechanism for each amount bank of the machine embodying the instant invention comprises companion scissors-like members with a complementary movement. In adding operations these members position their associated indicator and type wheel differential actuators and the wheels of the selected totalizer commensurate with the value of the depressed amount keys and said actuators in turn position their corresponding indicating mechanism and printing wheels commensurate with the value of the depressed amount keys. In this type of differential mechanism the actuators are not returned to a neutral or zero position at the end of machine operation but remain in the positions in which they were set by the companion members during the machine operation. Consequently in the succeeding operation the actuators are moved from the positions in which they were set during the preceding operation directly to their new positions. In totalizing operations the corresponding wheels of the selected totalizer position the scissors-like companion members commensurate with the amount on said totalizer wheels and said companion levers in turn position the actuators and the actuators in turn position the indicators and the type wheels commensurate with the amounts on the wheels of the totalizer.

35

For a full disclosure of the differential mechanism outlined above reference may be had to Letters Patent of the United States No. 1,792,569 and No. 1,899,455, issued respectively February 17, 1931 and February 28, 1933, to Ernst Breitling.

40

If it is desired to repeat the immediately preceding operation, the operator depresses the repeat starting bar, or in the modified form moves the total-control lever to repeat position. This actuates mechanism that locks the indication and type wheel differential actuators for the amount banks in the positions in which they were set in the preceding operation. The actuators then position the companion levers to repeat the amount of the preceding operation.

With this type of repeat mechanism an amount may be repeatedly added in one or more totalizers and amounts may be transferred from one totalizer to one or more of the remaining totalizers.

55

by reading or resetting the first-mentioned totalizer and by adding this amount in the desired totalizers in a subsequent repeat operation. In many of the well known machines of this type it is necessary that the operator have knowledge of a succeeding repeat operation in order to set up a condition in the present operation to effect said repeat operation. However, in the machine embodying this invention no knowledge is necessary on the part of the operator of a subsequent repeat operation, as all that is necessary in case it is desired to repeat an operation is to manipulate the repeat control mechanism.

In the following pages mechanism pertinent to the present invention will be described in detail.

DETAILED DESCRIPTION

Framework

Most of the mechanism of this machine is contained between and supported by a right side frame 30 and a left side frame 31 (Fig. 4) secured to a machine base (not shown). The entire machine is enclosed in a suitable cabinet 25 (not shown) which is in turn secured to the machine base.

Amount keys and their associated differential mechanism

The instant machine has a plurality of denominational amount banks 32 (Figs. 1 and 4) supported by a rod 33 and a bar 34 extending between the frames 30 and 31. Inasmuch as these amount banks and their associated differential mechanisms are exactly alike, it is believed sufficient to describe one such amount bank and its associated differential mechanism.

Depressing one of the amount keys 35 moves the lower end of the stem thereof in the path of a plate 37 secured to a main differential lever 38 and also moves said stem in the path of a nose 39 of an auxiliary differential lever 40, both of said levers being pivotally supported on a shaft 41 journaled in the frames 30 and 31. The segmental lower end of the main lever 38 (Figs. 1 and 4) has therein teeth which mesh with a sector 42 secured to a differential sun wheel 43 turnably mounted on a shaft 44 opposite ends of which are journaled in the frames 30 and 31. The auxiliary differential lever 40 has a segmental extension with gear teeth which mesh with a sector 45 loose on the shaft 44 and forming a support for a planet wheel 46 which connects the sun wheel 43 to a similar sun wheel 47, secured 55 to the shaft 44.

Depressing an amount key 35 causes a stud 48 thereon, in cooperation with an angular slot in a control plate 49, pivotally connected by symmetrical links 50 and 51 to the key frame 32, to impart clockwise rocking movement to said control plate 49. Clockwise movement of the control plate 49 causes the link 51 in cooperation with a bent-over ear 52 of a zero stop pawl 53 to rock said stop pawl clockwise about its pivot 54 and against the tension of a spring 55. Clockwise movement of the pawl 53 moves a hook 56 thereof out of the path of an extension of the main differential lever 38.

During each machine operation the shaft 44 is rocked first counterclockwise, as viewed in Fig. 1, and then back to normal position. This "to and fro" movement of the shaft 44, by means of the sun wheel 43 in cooperation with the planet pinion 46 and the sun wheel 47, causes the 75 companion differential levers 38 and 40 to move

toward each other in scissors fashion until the progress of one of said levers is interrupted by engagement thereof with the stem of the depressed amount key. The differential lever that is not restrained continues its movement until it also engages the stem of the depressed key. As the differential levers 38 and 40 move together in the manner explained above one of said levers engages a stud 57 in a type wheel and indicator differential plate 58 loose on the shaft 41, and moves said plate 58 in unison therewith until the stud 57 is held in the tong-like embrace of the levers 38 and 40, and positioned thereby commensurate with the value of the depressed amount key.

The differential positioning of the plate 58 by means of a pinion 60 is transmitted to a gear 61, which in turn sets an indicator for that particular bank commensurate with the value of the depressed amount key. Differential positioning of the plate 58 is transmitted, by means of teeth thereon in cooperation with a worm wheel 62 secured on a shaft 63 journaled in a cross frame 64, to the type carrier for that particular bank. The corresponding wheel 94 (Fig. 1A) of the selected totalizer is rocked into engagement with a gear 95 operatively connected to the main differential lever 38 by gears 96, 97, and 42, after said lever has been positioned by the depressed amount key, and return movement of said lever adds an amount on the totalizer wheel corresponding to the value of the depressed amount key.

Immediately after the differential levers 38 and 40 have completed positioning of the plate 58 in the manner explained above, an alining mechanism (not shown) retains said plate in its set position throughout the remainder of the machine operation and until the beginning of the succeeding machine operation. It is therefore obvious that the plate 58 and its associated indicator and type wheel remain in their set positions at the end of machine operations.

In total taking operations the main differential lever 38 in cooperation with the auxiliary lever 40 positions the plate 58 in accordance with the amount on the wheel of the selected totalizer. This is accomplished during the initial movement of said levers 38 and 40.

Repeat mechanism

The amount of the preceding operation, whether the result of an adding or a total taking operation, may be repeated in succeeding machine operations by means of a manipulative device that locks the plate 58 in its pre-set position and thus the stud 57 controls the positioning of the differential levers 38 and 40 exactly as they were controlled during the preceding operation by the depressed amount key. It is obviously unnecessary as well as undesirable to depress amount keys in repeat operations and to prevent this an interlocking device rendered effective by the repeat manipulative member locks the amount keys against depression during repeat operations.

In its preferred form the present machine is provided with two starting bars (Fig. 2), a regular starting bar 65 and a repeat starting bar 66. The regular starting bar 65 is used to release the machine for operation in all operations except repeat operations.

Depressing the repeat bar 66 by means of a stud 67 therein, in cooperation with an angular slot 68 in a control plate 69, imparts counter-

clockwise movement to said control plate. The plate 69 is rockably mounted on a frame 70, that supports the starting bars 65 and 66, by means of a lever 71 pivoted at 72 to the frame 70 and a link 73. Counterclockwise movement of the plate 69 and incidental similar movement of the lever 71 moves a rearward extension of said lever away from a stud 74 secured in one arm of a bell crank 75 fast on a sleeve 76 loose on a rod 77 supported by the frames 30 and 31.

Also secured on the sleeve 76 is an arm 78 connected by a rigid bar 79 to a similar arm 80 (Fig. 4) rotatably supported by the rod 77. Counterclockwise movement of the lever 71 permits a spring 81, the upper end of which is connected to the arm 78, to rock the rigid transverse bar 79 into engagement with a tooth space in the top edge of the plate 59. This locks the plate 59 in the position in which it was set during the preceding machine operation.

In adding operations, depressing an amount key rocks the zero stop pawl 53 (Fig. 1) out of the path of the lever 38. However, as no amount key is depressed in repeat operations, it is necessary to provide other means to rock the zero stop pawl 53 to ineffective position. A pitman 81 (Fig. 2) one end of which is pivoted to the plate 69 and the other end of which is bifurcated to straddle a rod 82 extending between the frames 30 and 31 moves in unison with said plate 69 upon depression of the repeat starting bar 66. Movement of the pitman 81 by means of a stud 83 therein in cooperation with the forked upper end of a bell crank 84 secured to one end of a sleeve 116 loose on a rod 85 extending between the frames 30 and 31, imparts counterclockwise movement to said bell crank 84. The lower end of the bell crank 84 is bifurcated to embrace a stud 86 in an arm 87 loose on the sleeve 116 and connected by a transverse rod 88 to a similar arm 89 (see also Fig. 4). It is therefore obvious that the arms 87 and 89 and the rod 88 move counterclockwise in unison with the bell crank 84 when the repeat bar 66 is depressed. Counterclockwise movement of the rod 88 (Fig. 1) causes said rod, in cooperation with an angular extension of the zero stop pawl 53, to rock said pawl clockwise to remove the hook 56 thereof out of the path of the differential lever 38. After the zero stop pawl 53 is moved to ineffective position the differential levers 38 and 49 move towards each other in a scissors-like manner until positioned by the stud 57 in the plate 59 which is locked in the position in which it was set in the preceding operation by the bar 79 (Fig. 2). This causes the amount of the previous operation to be repeated.

A cam 90 (Figs. 2 and 4) is secured to a gear 93 loose on a rod 91 supported by the frames 30 and 31. The gear 93 and the cam 90 are driven one counterclockwise revolution each machine operation. Near the end of machine operation the periphery of the cam 90, in cooperation with a stud 92 in the bell crank 75, rocks said bell crank counterclockwise to disengage the locking bar 79 from the plate 59. Also near the end of machine operation the repeat starting bar 66 is released and is spring-returned upwardly to un-depressed position. Return movement of the repeat bar 66 causes the stud 67 in cooperation with the angular slot 68 to return the plate 69 and the lever 71 clockwise to normal position, in which position said lever 71 engages the stud 74 in the bell crank 75 when the lobe of the cam 90 moves beyond the stud 92, to retain the lock-

ing bar 79 out of engagement with the teeth in the differential plate 59. Return movement clockwise of the plate 69 by means of the pitman 81 and the bell crank 84 (Figs. 1 and 2) returns the rod 88 also clockwise to permit the zero stop pawl 53 to be returned counterclockwise to effective position by the spring 55.

It is obvious from the foregoing description that by simply depressing the repeat starting bar 66 the amount of the preceding operation may be repeated for the purpose of entering said amount in one or more of the machine totalizers.

Interlock between the amount keys and the repeat starting bar

Depressing one of the amount keys 35 (Fig. 1) actuates interlocking mechanism that prevents depression of the repeat starting bar 66 (Fig. 2) and likewise depressing the starting bar 66 actuates the interlocking mechanism to prevent depression of an amount key 35. This interlocking mechanism will now be described.

Pivoted to the upper end of the control plate 49 (Fig. 1) is a pitman 98, the upper end of which is bifurcated to embrace the rod 82. The pitman 98 carries a pin 99 adapted to cooperate with an arm 100, secured to a sleeve 101, loose on a rod 102, supported by the frames 30 and 31. Also secured to the sleeve 101 (Fig. 2) is an arm 103, adapted to cooperate with the stud 83 in 30 the pitman 81.

Depressing one of the amount keys 35 moves the control plate 49 and the pitman 98 upwardly, causing the stud 99 to impart counterclockwise movement to the arm 100, the sleeve 101 and the arm 103. This moves the arm 103 into contact with the stud 83 thereby blocking downward movement of the pitman 81 and the control bar 69 to obstruct depression of the repeat bar 66 when an amount key is depressed.

Likewise depressing the repeat starting bar 66 moves the stud 83 into contact with the arm 103 to block counterclockwise movement of said arm and the arm 100 (Fig. 1) to prevent depression of an amount key 35 when the repeat starting bar 66 is depressed.

Total control lever

The machine embodying the preferred form of this invention is provided with a total control lever 104 (Figs. 3 and 4) having three positions of adjustment, namely, "Add", "Read", and "Reset". Interlocking mechanism between the total control lever 104, the repeat starting bar 66 and the amount keys 35 prevents depression of said repeat bar 66 and said amount keys 35 when the total control lever 104 is out of adding position. Likewise the interlocking mechanism locks the total control lever in adding position when either an amount key 35 or the repeat bar 66 is depressed. Such mechanism will now be described.

The total control lever 104 is rotatably supported on the shaft 41 and has a segmental portion with teeth which mesh with a gear 105, revolvable on the rod 91. The gear 105 is secured to a locking disk 106, with an arcuate locking slot 107 which coincides with a bent-over extension 108 of an arm 109 when the total control lever 104 is in adding position, as shown in Fig. 3. The arm 109 is secured to a sleeve 110 loose on the rod 85, said sleeve having also secured thereto an arm 111 (Fig. 1) which extends in the path of the stud 99 in the pitman 98.

Depressing an amount key 35 moves the plate 75

49, the pitman 98 and the stud 99 upwardly to impart clockwise movement to the arm 111, the sleeve 110 and the arm 109. Clockwise movement of the arm 109 moves the extension 108 into the 5 slot 107 to lock the total control lever in adding position when an amount key is depressed. A spring 112 normally maintains the extension 108 out of the slot 107 when an amount key is not depressed and urges the arm 111 counterclockwise into contact with the stud 99. When the 10 total control lever 104 is away from adding position the slot 107 is out of alignment with the extension 108 and the periphery of the disk 106 blocks clockwise movement of the arms 109 and 15 111 to prevent depression of an amount key 35.

The disk 106 has another arcuate slot 113 which coincides with a bent-over projection 114 of an arm 115 when the total control lever 104 is in adding position. The arm 115 is secured on one 20 end of the sleeve 116 to the other end of which is secured the bifurcated bell crank 84 (Fig. 2). The sleeve 116 is rotatably mounted on the sleeve 110 which is turnably mounted on the rod 85. Depressing the repeat starting bar 66 imparts 25 downward movement to the control plate 69 and the pitman 81 causing the stud 83 to rock the bell crank 84, the sleeve 116 and the arm 115 (Fig. 3) counter-clockwise to move the projection 114 into the slot 113 to lock the total control lever 104 in adding position when the repeat bar 66 is depressed. Moving the total control lever 104 out of adding position moves the notch 113 out of alignment with the projection 114, permitting the periphery of the disk 106 to block 30 35 counterclockwise movement of the arm 115, which by means of the sleeve 116 and the bell crank 84 blocks downward movement of the pitman 81 and the control bar 69 to prevent depression of the repeat release bar 66 when the total control 40 lever 104 is out of adding position.

MODIFIED FORM

A modified form of repeat mechanism is illustrated in Figs. 5 and 6, in which a total control 45 lever 119, similar to the total control lever 104, has four positions—viz., "Add", "Read", "Reset" and "Repeat". When the total control lever 119 is in "Repeat" position, the amount keys are locked against depression and the differential control plate 59 is locked in the position to which it was adjusted in the preceding operation. Depressing the regular starting bar 57 sets the 50 machine in motion to repeat the amount of the preceding operation. It will be understood that moving either the total control lever 104 of the preferred form, or the total control lever 119 of the modified form, away from adding position rocks the zero stop pawl 53 (Fig. 1) to ineffective position, in order that the stud 57 in the plate 55 60 59 may position the companion scissors levers 38 and 40 in the manner explained hereinbefore.

As in the preferred form, the total control lever 119 has a segmental portion with teeth which mesh with a gear 120 secured to a control disk 65 121 rotatably supported by the rod 91. The disk 121 (Fig. 5) has in the left face thereof a camming groove 122 into which extends a stud 123 carried by an arm 124 secured to the righthand end of a sleeve 125 revolvable on the rod 77. Secured to the left end of the sleeve 125 is an arm 70 75 126 which supports one end of a transverse locking bar 127, the other end of which is supported by an arm (not shown) similar to the arm 126, and loose on the rod 77. The arm 126 and the locking bar 127 are similar to the arm 78 and

the locking bar 79 (Fig. 2) of the preferred form, and the locking bar 127 cooperates with the teeth on the upper portion of the plate 59 in exactly the same manner as the bar 79.

The configuration of the cam groove 122 is 5 such that when the total control lever 119 is moved to "Repeat" position, clockwise movement is imparted to the arm 124, the sleeve 125, the arm 126 and the locking bar 127, to engage said locking bar with the teeth of the differential plate 59 to lock said plate in the position to which it was set in the preceding operation. Releasing the machine for operation by means of the starting bar 65 causes the amount of the preceding operation to be repeated in the manner 10 explained above. It will be noted that when the total control lever 119 is in "Add", "Read", or "Reset" position the cam groove 122 maintains the locking bar 127 out of engagement with the plate 59. 15 20

The disk 121 has an arcuate slot 128 which is aligned with the extension 108 of the arm 109 when the total control lever 119 is in adding position. Depressing an amount key 35 (Figs. 1 and 5) through the plate 49, pitman 98 and stud 99 25 30 rocks the arm 111, sleeve 110 and arm 109 clockwise to engage the extension 108 with the slot 128 to lock the lever 119 in adding position. Moving the lever 119 away from adding position rotates the disk 121 clockwise to move the slot 128 35 out of alignment with the extension 108 and the periphery of the disk 121 obstructs clockwise movement of the arm 109 to prevent the depression of an amount key 35.

While the form of mechanism shown 35 and described is admirably adapted to fulfill the objects primarily stated, it is to be understood that it is not intended to confine the invention to the one form or embodiment herein disclosed, for it is susceptible of embodiment in various 40 forms, all coming within the scope of the claims which follow.

What is claimed is:

1. In a machine of the class described, having a plurality of amount keys, the combination 45 of amount differential means, including companion members with complementary movement, said companion members adapted to be positioned for adding and total taking operations; a member arranged to be positioned by the companion members in adding and total taking operations, and adapted to control the positioning of the companion members in repeat operations; means to lock the member in set position; a manipulative device; and means operated by the 50 55 manipulative device to render the locking means effective to lock the member in set position to cause said member to position the companion members to repeat the amount of the preceding 60 operation. 65

2. In a machine of the class described, having a plurality of amount keys, the combination of companion levers with a complementary scissors movement adapted to embrace the stem of a depressed amount key to be positioned 65 70 75 commensurate with said amount key for adding amounts; a member arranged to be set by the companion levers at the time said companion levers are positioned by the depressed amount key, said member adapted to remain in set position until the succeeding operation; teeth on the member; an element cooperating with the teeth to lock the member in set position; a manipulative device; and means operated by the manipulative device to render the locking means 75

effective to cause the amount of the preceding operation to be repeated in the succeeding operation.

3. In a machine of the character described, 5 the combination of companion levers with a complementary scissors movement; a member adapted to be positioned by the companion levers in adding and total taking operations, and adapted to control the position of said companion levers 10 in repeat operations, said member adapted to remain in set position until the succeeding operation; means to lock the member in set position; a manipulative device; and means whereby the manipulative device renders the locking 15 means effective for the succeeding operation to retain the differential member in the position in which it was set in the preceding operation to position the companion levers commensurate therewith.
- 20 4. In a machine of the character described, capable of adding, totalizing and repeat operations, the combination of a settable differential member; means including two companion levers with complementary scissors movement to set 25 the differential member in adding and total taking operations; said companion levers adapted to be positioned under control of the member in repeat operations; and means effective in repeat operations to retain the differential member in 30 the position in which it was set by the companion levers in the preceding operation to cause said differential member to control the position of the companion levers commensurate therewith.
- 35 5. In a machine of the class described, capable of adding, totalizing and repeat operations, the combination of means to initiate repeat operations; a settable differential member arranged to remain in set position until the succeeding operation; companion levers with complementary scissors movement, said companion levers setting the differential member in adding and total taking operations and positioned under control of said differential member in repeat operations; 40 normally ineffective means to lock the differential member in set position; and means including a rockable element associated with the initiating means to render the locking means effective to cause the differential member to control 45 the position of the companion levers commensurate therewith.

6. In a machine of the class described, capable of repeat operations, having a plurality of amount keys, the combination of a settable differential member adapted to remain in set position until the succeeding operation; means including companion levers to engage a depressed amount key and set the differential member accordingly, said companion levers positioned under control 55 of the differential member in repeat operations; means effective in repeat operations to retain the differential member in the position in which it was set in the preceding operation by the companion members and the depressed amount 60 key; a manipulative device; and means positioned by the manipulative device to render the retaining means effective.

7. In a machine of the character described, the combination of a differential member adapted 65 to be set during a machine operation and remain set until the succeeding operation; means to lock the differential member against any movement when it is in set position; means to condition

the machine for a repeat operation; a rockable element actuated by the conditioning means; and a part operatively connecting the element to the locking means to cause the conditioning means to render the locking means effective to 5 lock the differential member in the position in which it was set in the preceding operation to retain the setting of said differential member in the succeeding operation.

8. In a machine of the class described, the 10 combination of a rotatable differential member adapted to be set during a machine operation and remain set until the succeeding operation; means to rotate the differential member; means to lock the differential member against rotation 15 from its set position; a manipulative device; a cam operated by the manipulative device; an element intermediate the cam and the locking means to cause movement of the manipulative device to a certain position to render the locking 20 means effective to lock the differential member in the position in which it was rotated to the preceding operation to retain the setting of said differential member in the succeeding operation.

9. In a machine of the class described, having a plurality of amount keys, the combination of a differential member adapted to be positioned during a machine operation and to remain so positioned until the succeeding operation; means to position the differential member commensurate with a depressed amount key; means rendered effective prior to the succeeding operation to lock the differential member in set position to retain the positioning of said differential member during the succeeding operation; a 30 manipulative device; means connecting the manipulative device to the locking means to cause movement of said manipulative device to render the locking means effective; a control member movable to a plurality of positions; a disk operatively connected to the control member and having therein two notches; an element actuated by the connecting means and adapted to enter one of the notches upon movement of the manipulative device to lock the control members in 35 a particular position; and a piece arranged to enter the other notch in the disk upon depression of an amount key to lock the control member in said particular position, said disk in cooperation with the element and the piece, adapted 40 to prevent movement of the manipulative device and the depression of an amount key when the control member is out of said particular position.

10. In a machine of the class described, the 45 combination of a manipulative device to control repeat operations of the machine; complementary movable differential members; an element adjustable differentially by the complementary 50 movable differential members according to the differential adjustment thereof; locking means for the element, normally in unlocking position; and connections between the manipulative device and the element to move the locking means into locking position upon operation of the manipulative device to lock the element in the position to which it was adjusted in the preceding operation, whereby the element controls the positioning of the differential members during the 55 operation in which the manipulative device is 60 operated to repeat the amount of the preceding operation.

ERNST BREITLING.

CERTIFICATE OF CORRECTION.

Patent No. 2,111,909.

March 22, 1938.

ERNST BREITLING.

It is hereby certified that error appears in the printed specification of the above numbered patent requiring correction as follows: Page 5, second column, line 22, claim 8, for the word "in" second occurrence, read to; same line and claim, for "to" read in; and that the said Letters Patent should be read with these corrections therein that the same may conform to the record of the case in the Patent Office.

Signed and sealed this 3d day of May, A. D. 1938.

(Seal)

Henry Van Arsdale,
Acting Commissioner of Patents.
